UNITED STATES PATENT OFFICE.

JOHN W. PARKS, OF MUSKOGEE, OKLAHOMA, ASSIGNOR OF ONE-HALF TO WILLIAM M. HARRISON AND ONE-EIGHTH TO E. R. CROOKER, OF LAUDERDALE, MISSISSIPPI, AND ONE-FOURTH TO THOMAS DUNCAN, OF MUSKOGEE COUNTY, OKLAHOMA.

CRUDE-OIL BURNER.

No. 909,328.

Specification of Letters Patent.

Patented Jan. 12, 1909.

Application filed April 6, 1908. Serial No. 425,331.

To all whom it may concern:

Be it known that I, JOHN W. PARKS, citizen of the United States, residing at Muskogee, in the county of Muskogee and State of Oklahoma, have invented certain new and useful Improvements in Crude-Oil Burners, of which the following is a specification.

My invention has relation to new and useful improvements in crude oil burners, and has, as one of its objects, to produce such a burner as will be adapted for use in cooking stoves, furnaces or other heating devices.

A further object of my invention is to produce an oil burner, so constructed that the full possible combustible value of the oil will be attained therefrom. In carrying out this idea, I have so arranged the several parts of my invention that the oil is spread over a greater surface, thus giving a greater generating area than has been usually attained in oil burners of the class. Furthermore I believe by the use of my improved burner, a greater draft will be caused, thus causing greater heat as a result of greater combustion.

With these and other objects in view, my invention consists of the novel construction and arrangement of parts as are hereinafter described in the following specification, and illustrated in the accompanying drawings forming a part thereof; said novelty of construction being particularly pointed out in the claims hereunto appended.

Reference being had to the drawings: Figure 1 is a perspective view of my crude oil burner, complete, showing the same resting on a fire grate. Fig. 2 is a top plan view of the above, having the caps removed. Fig. 3 is a cross sectional view of my invention on the line 3—3 of Fig. 2. Fig. 4 is a bottom plan view of the cap. Fig. 5 is a perspective view of the chamber.

Referring more particularly to the drawings, the pan 1, of my burner rests on the grate 2, of a stove or furnace, or other heat generating device. The said pan 1, is filled to the top edge of the trough 3, with asbestos or some other non-combustible material. Secured to the rear, upper, left-hand corner 50 (Fig. 1) of said pan, is an igniter cylinder 4, having a flange portion 5, secured to the upper edge thereof. Formed to the lower edge on the inner periphery of said igniter cylinder, is a flange portion 6, for the purpose

of allowing the serrated portion 7, formed on the outer extending portion of the bottom of the chamber 4¹, to rest thereon. Formed or secured to the upper edge on the outer periphery of said chamber 4¹, is a flange portion 6¹. Running downwardly and slanting outwardly from said flange portion 6¹, to said serrated portion 7, is an oil duct 8, for the purpose of conveying the oil from said chamber to said trough 3, where the said oil overflows, spreads over the surface and is absorbed by said asbestos on said pan 1. Passing through the flange portion 5, and terminating over the mouth of the chamber 4¹, is an oil vent 10, for the purpose of supplying oil to said chamber 4¹, when it is more convenient not to have the air chamber 18, directly over the flame. The perforated cap 9, has formed on its under face, a series of small air chambers 11, for the purpose of retaining a certain amount of air fed through the outer part of said cap 9.

A pipe 13, conducts the fuel from the tank 14, into a funnel 16, supported at the upper end of a pipe 13¹. Said pipe 13, is provided with a stopcock at its lower end for the regulation of the flow of said fuel. Said funnel is secured to the lower end of the upper pipe by means of a bridge 17, and the same is adapted to catch drippings from the upper of said pipes, when the stopcock 15, is turned on. The small end of said funnel is formed or secured to the upper end of the lower pipe and conducts the oil or fuel therein. The pipe 13¹, has an enlarged portion 18, said enlarged portion being cylindrical in shape, and adapted for the purpose of holding a reserve supply of air to aid in combustion when said stopcock allows the oil to pass from said pipe into said chamber 4¹. The oil, upon passing into said funnel, is conducted into said enlarged portion, carrying with it a certain quantity of air. However, when the enlarged portion 18, becomes heated, the oil, as it passes therein, is partially transformed into gas, thus materially aiding in the combustion going on at the other end of the pipe 13¹.

It is pointed out that when it is desired to light my improved burner, said stop-cock is turned on, the oil dripping from said pipe 165 into said funnel. The oil then runs into chamber 4¹, is absorbed by the asbestos or other non-combustible material contained

therein, overflows said chamber, runs into said trough 3, by means of said oil duct 8, when it is ignited. The trough 3, overflows, allowing the oil to spread over and be absorbed by the non-combustible material in said pan 1, thus making two distinct fires, namely, one emanating from the pan 1, the other emanating from the chamber 4.

Although I have specifically described my invention, I may claim the right to make such alterations and modifications as do not depart from the spirit of my claims, and as fall within the scope of my invention.

Having described my invention, what I claim as new, is:

1. In a device of the character described, the combination of a pan having a longitudinal trough running from end to end, said trough secured to the inner face of the rear wall of said pan, an igniter chamber secured to one of the corners thereof, a second chamber, means formed at the lower edge of the igniter chamber to support said second chamber, said second chamber adapted to receive a non-combustible substance, a cap as means to cover up said first-named chamber, said cap being perforated, means to saturate the non-combustible material in the second-named chamber with fuel and means for regulating the supply of said fuel.

2. In a crude oil burner, comprising a pan having a longitudinal trough running therein from end to end, an igniter chamber secured to one of the corners of said pan, said igniter chamber being provided with a flange portion formed at its lower edge on the inner periphery thereof, said igniter chamber being further provided with a flange portion secured to its upper edge, and on the outer periphery thereof, a second chamber provided with a bottom which has an outwardly extending serrated portion, said second-named chamber further provided with a collar at its upper edge on the outer periphery thereof and further provided with an oil duct running slantingly downwardly from the upper flange to said serrated portion of the bottom, means to cover up said first-named chamber consisting of a perforated cap, means to supply oil to said second-named chamber, and means to regulate the same.

3. In a crude oil burner comprising a pan having a trough therein, an igniter chamber secured to one of the corners of said pan, a second chamber adapted to be incased by said igniter chamber, said second chamber adapted to receive a non-combustible material, a cover for said igniter chamber com-

prising a perforated cap, said cap having formed on its under face a series of air chambers, means to supply oil to said second chamber, and means for the regulation of the same.

4. In a crude oil burner, comprising a pan having a trough therein, an igniter chamber secured to one of the corners of said pan, a second chamber adapted to be incased by said igniter chamber, said second chamber adapted to receive a non-combustible material, a cover for said igniter chamber comprising a perforated cap, means to supply oil to said second chamber, said means consisting of a pipe having mounted on its upper end an oil tank, and a second pipe having an enlarged portion secured to its outer surface directly above said perforated cap, a funnel provided just above said enlarged portion, the end of said first named pipe extending into the mouth of said funnel, means comprising a stop cock adapted to allow oil to drip into said funnel, substantially as shown and described.

5. In a crude oil burner comprising a pan provided with a trough, said pan adapted to rest on a fire grate, an igniter chamber and a second chamber, said second chamber adapted to be incased by said igniter chamber, a perforated cap adapted to cover up the mouth of said igniter chamber, said pan and said second chamber being filled with a non-combustible material, means to furnish oil to said second chamber and means to furnish oil from said second chamber to said pan.

6. In an oil burner of the class described, comprising a pan, an igniter chamber and a second chamber which is incased by said igniter chamber, means to furnish oil to said second chamber, said means comprising an oil pipe having a stop cock to regulate the flow of oil, and further consisting of a funnel and a second pipe provided with an enlarged portion, said funnel situated just below said stop cock and being secured to said first-named pipe by means of a bridge, said enlarged portion being situated just below the funnel and secured thereto, said funnel and enlarged portion affording means to mix the combustible material with air, substantially as shown and described.

In testimony whereof I affix my signature, in presence of two witnesses.

JOHN W. PARKS.
